UNITED STATES PATENT OFFICE

1,922,293

MINING MACHINE

Morris P. Holmes, Claremont, N. H., assignor to
Sullivan Machinery Company, a Corporation
of Massachusetts

Application July 24, 1931. Serial No. 552,936

49 Claims. (Cl. 262—30)

This invention relates to mining machines and more particularly, but not exclusively, to improvements in the feeding mechanism of a coal mining machine of the flexibly fed, continuous cutter, bottom cutting type.

An object of this invention is to provide an improved coal mining machine. Another object is to provide an improved mining machine feeding mechanism. A further object is to provide improved flexible feeding means for a mining machine of the continuous cutter, bottom cutting type. Yet another object is to provide an improved feeding mechanism particularly adapted for use in mining machines of the long-wall type. Still another object is to provide an improved flexible feeding means for a coal mining machine wherein a feed operating member cooperating with a flexible feeding element is employed having an improved plural speed transmission mechanism whereby the feed operating member is driven in an improved manner in a direction to draw in its cooperating flexible feeding means at either a relatively low cutting speed or a relatively high machine moving speed. Yet another object is to provide improved plural speed transmission mechanism for a mining machine feeding mechanism wherein a comparatively small number of moving parts are employed and which is of an extremely rugged and compact construction. These and other objects of this invention will, however, hereinafter more fully appear in the course of the following description and as more particularly pointed out in the appended claims.

In the accompanying drawings there is shown for purposes of illustration one form and a modification which the invention may assume in practice.

In these drawings,—

Fig. 1 is a plan view of a longwall coal mining machine having embodied therein the illustrative form of the improved feeding mechanism.

Fig. 2 is an enlarged horizontal sectional view taken substantially on line 2—2 of Fig. 3 and illustrating the improved plural speed transmission mechanism and the associated control means.

Fig. 3 is a central longitudinally extending vertical sectional view taken substantially on line 3—3 of Fig. 2.

Fig. 4 is a detail vertical sectional view taken on line 4—4 of Fig. 2.

Fig. 5 is a transverse vertical sectional view taken on line 5—5 of Fig. 2.

Fig. 6 is a detail view illustrating the improved control means for the transmission mechanism.

Fig. 7 is a fragmentary view similar to Fig. 2 illustrating a slightly modified form of construction.

In the illustrative embodiment of the invention shown in Figs. 1 to 6 inclusive, the improved flexible feeding means is shown embodied in a coal mining machine of the continuous cutter, bottom cutting, longwall type generally comprising a frame 1 having a plane bottom surface 2 and adapted to rest upon and slide over the mine floor. Pivotally mounted at 3 for horizontal swinging movement about a vertical axis 70 is a cutter bar 4 carrying on its margin a usual endless cutter chain 5. As is usual in mining machines of the type disclosed, the cutter bar 4 is swingable into different angular positions relative to the machine frame and is adapted to be locked in its different positions by a rotary locking pin 6 carried by the cutter bar and engageable with notches 7 formed in the outer periphery of a flange 8 integral with the frame 1. The machine is fed over the mine floor at a relatively low cutting speed and at relatively high machine moving speed by usual feed operating member, herein a haulage or cable winding drum 9, arranged for rotation about a vertical axis and having wound thereupon a usual flexible feed cable 10. Arranged at opposite sides of the haulage drum 9 are guide sheaves 11 for guiding the feed cable relative to the feed drum during the various operations of the machine. The feed cable is connectible to the locking pin 6 in a usual manner, as indicated in dotted lines in Fig. 1, and when the locking pin is released, the feed cable may be wound in by the haulage drum to effect swinging of the cutter bar about its pivot. During feeding of the machine along the coal face, the feed cable is extended from the haulage drum 9 in the manner indicated in full lines in Fig. 1 and is connected at its free end to a suitable anchor located in advance of the machine adjacent the coal face, and as the cable is wound in, the machine is fed bodily over the mine floor in the manner well understood in the art. The cutter chain 5 and the haulage drum 9 are driven by a motor 12, which may be of the reversible electric type, having its power shaft 13 horizontally disposed and extending longitudinally of the machine, the motor being indicated in dotted lines in Fig. 1.

Now referring to the improved plural speed

transmission mechanism between the motor power shaft and the haulage drum 9, it will be noted that keyed to the one end of the motor power shaft 13 is a spur pinion 14 meshing, as shown in Fig. 5, with an intermediate or idler gear 16. The gear 16 is suitably journaled on the stub shaft 17 mounted within the machine frame and meshes with a spur gear 18 keyed at 19 to a hollow transmission shaft 20. The shaft 20 is horizontally disposed and is arranged with its axis parallel with the power shaft axis, as shown in Fig. 2, and is journaled on a stationary shaft 21, the shaft 21 extending centrally through the hollow shaft 20 and fixed at its ends at 22 within the machine frame. Herein formed integral with the hollow shaft 20 is a worm 23, which is herein a fast speed worm, meshing with a fast speed worm wheel 24. Also meshing with the worm 23 is a worm wheel 25 fixed at 26 to a vertical shaft 27 arranged for rotation about a vertical axis. This shaft is herein made hollow and is journaled at its ends on stub shafts 28, 29 fixed within bores 29, 29 formed in the machine frame, the upper bore being formed in the detachable top plate of the frame housing the feeding mechanism. Keyed at 30 to the upper end of the shaft 27 is a spur gear 31 meshing with a spur gear 32 keyed at 33 to a vertical shaft 34 herein arranged parallel with the shaft 27 and in the same longitudinally extending vertical plane. The shaft 34 is likewise made hollow and is journaled in a similar manner on stub shafts 35, 36, the former being fixed within a bore 37 formed in the detachable top plate of machine frame, while the latter is formed integral with a detachable bearing retaining cap 38. Herein secured to the shaft 34 is a worm 39 which meshes with a worm wheel 40 keyed at 41 to a hollow shaft 42 herein aligned with the shaft 20 and likewise journaled on the shaft 21. Formed integral with the shaft 42 is a worm 43, which herein constitutes the slow speed worm, meshing with a slow speed worm wheel 44. The worm wheels 24 and 44 are arranged in parallel relation on vertical axes lying in the central longitudinal vertical plane of the machine as shown in Fig. 2, and respectively drive through multiple disc clutches 45 and 46 and interlocking mechanisms 47 and 48 vertical shafts 49 and 50 respectively. The shafts 49 and 50 are herein arranged coaxial with the worm wheels 24 and 44 respectively, and have respectively secured thereto at their lower ends, and driven thereby, spur pinions 51 and 51^a meshing with the teeth of an internal gear 52 herein formed integral with the haulage drum 9, as clearly shown in Fig. 3. As the means for journaling the worm wheels 24, 44 and shafts 49, 50 within the machine frame and the structure and control of the disc clutches and interlocking mechanisms are identical in design, the description of the structure of the drive and controlling elements coaxial with the worm wheel 24 will suffice for both. The worm wheel 24 has its upper and lower hubs journaled in bearing sleeves 53, 53 supported by a hollow shaft 54 surrounding the shaft 49 and suitably journaled within the machine frame. This worm wheel carries a series of clutch discs 55 interleaved with a corresponding series of clutch discs 56 carried by the hollow shaft 54. Surrounding the shaft 54 adjacent its upper end is a clutch applying member 57 connected through an anti-friction bearing 58 to an annular clutch member 59 slidably mounted on the enlarged portion 60 of the

shaft 54. When the clutch member 59 is moved downwardly from the position shown in Fig. 3, it engages plungers 61 and through these plungers transmits pressure to the discs of the friction clutch to frictionally connect the worm wheel 24 to the vertical shaft 54. The friction clutch 46 controlling the connection of the worm wheel 44 in driving relation with the haulage drum is provided with a similar clutch member 62 connected by an anti-friction bearing 63 to a clutch applying member 64. It will thus be seen that when the clutch 45 is applied and the clutch 46 released and the interlocking mechanism 47 is connected and the interlocking mechanism 48 is released, the haulage drum may be driven through the fast speed worm gearing 23, 24 in a direction to wind in its cooperating feed cable at a relatively high speed. When the clutch 46 is applied and the interlocking mechanism 48 connected, and the clutch 45 is released and the interlocking mechanism 47 disconnected, the haulage drum may be driven through the slow speed worm gearing 43, 44 at a relatively low speed.

Now referring to the interlocking mechanism 47, 48 for connecting the hollow shafts to the shafts 49, 50 respectively, it will be noted that each of the clutch elements 59, 62 is internally grooved at 65 and is provided with oppositely disposed cam surfaces 66 and 67. Projecting within the groove 65, when the latter is in the position shown in Fig. 3 are interlocking clutch plungers 68 slidably mounted within radial chambers 69 formed in the enlarged portion of the hollow shaft 54. Each of these plungers is grooved at 70 at their opposite sides to form recesses within which coiled springs 71 are arranged, the latter tending to hold the clutch plungers in their outermost or released position. The inner ends of these plungers when 115 in their inner connected position engage slots or grooves 72 formed in the shaft 47. Each of the clutch plungers is provided with inclined surfaces which are complementary to the cam surfaces on the clutch members 59 and 62. The 120 clutch members 59 and 62 have respectively co-operating therewith shipper yokes 73 and 74, the former fixed to an operating rod 75 and the latter to a hollow operating sleeve 76 arranged concentrically with and surrounding the rod. 125 The rod and sleeve are suitably rotatably supported within the machine frame and secured as by a pin to the outer extremity of the rod is a toothed clutch element 77, while formed on the outer end of the sleeve are clutch teeth 130 78. Slidably mounted on the rod is an operating handle 79 having formed on the opposite sides of its hub, clutch teeth 80 and 81. A suitable spring pressed plunger lock 82 carried within the grasping portion of the handle is provided for 135 locking the handle in its different angular positions. The handle 79 constitutes the common operating element for the clutch shipper yokes and when the handle is in the position shown in Fig. 2 with the teeth 80 thereon connected to the teeth 78 formed on the sleeve the sleeve may be rotated while the rod remains stationary, and as a result, the interlocking mechanism 48 is connected and the clutch 46 applied, while the interlocking mechanism 47 and the clutch 140 45 are released. When the handle 79 is moved outwardly to release the teeth thereon from the teeth on the sleeve and connect the teeth 81 with the teeth of the clutch element 77, the rod 75 may be turned while the sleeve remains sta- 145

tionary, and as a result, the interlocking mechanism 47 and clutch 45 may be connected while the other interlocking mechanism and clutch are released.

5 When the parts are in the position shown in Figs. 2 and 3, the clutch plungers 68 are held within the annular recesses 65 formed in the clutch elements 59 and 62 respectively with the inner ends of the clutch plungers wholly released from the groove formed in the shafts 49 and 50. When the clutch members 59 and 62 are in this position, the clutches 45 and 46 are both released. At this time, the haulage drum 9 may rotate freely relative to its drive mechanism, the shafts 49 and 50 upon rotation of the haulage drum turning freely within the hollow shafts 54. When it is desired to effect drive of the haulage drum in winding direction at a relatively low speed, that is a speed suitable for effecting feed of the machine during the cutting operation, the clutch 62 is shifted upon suitable manipulation of the operating handle 79 to cause a cam surface thereon to force the clutch plungers 48 inwardly into interlocking engagement with the grooves on the shaft 50, thereby connecting the shaft 50 to its hollow drive shaft 54. When the clutch member is further depressed, the plungers 61 are engaged and the discs of the clutch 46 forced into their engaged position. When the clutch member 62 is shifted upwardly, the friction clutch 46 is first released and the interlocking mechanism 48 thereafter disconnected. When it is desired to effect rotation of the haulage drum at a relatively high speed, the clutch member 59 is moved downwardly to first connect the interlocking mechanism 68 and thereafter apply the friction clutch 45. Due to the use of the common control handle 79, it is impossible to simultaneously connect the interlocking mechanisms and simultaneously apply the friction clutches. Before the provision of the interlocking mechanisms between the driving and driven shafts drag rotation was imparted by the clutch discs of the disc clutches, even when the latter were in their released position, which caused the haulage drum to rotate. Under certain conditions, for instance when the motor was reversed, it has been found that the drag in the clutch discs, even when in their released position, was sufficient to cause the haulage drum to rotate to unwind the feed cable and some danger of causing the latter to become dangled and twisted. By the provision of the interlocking mechanisms between the disc clutches and the drive shafts, it is possible, when the clutch mechanisms are released, to relieve entirely the haulage drum from any action of the clutch discs, so that when the clutch operating means are in their neutral position, the haulage drum remains stationary or may be freely manually rotated. This is an especially desirable feature when it is desired to unwind the feed cable from the haulage drum by hand.

65 In the modification shown in Fig. 7, the spur pinion 14 meshes with a spur gear 85 which has rotatable therewith and drives a spur gear 83 meshing with a spur gear 87. The latter gear is fixed to a shaft 88 herein arranged parallel with the motor shaft and suitably journaled within the machine frame. Herein formed integral with the shaft 88 is a spur pinion 89 meshing with a spur gear 90 keyed to a shaft 91 herein arranged parallel with the shaft 88, as illustrated. Keyed to and driven by the shaft 91 is

a spur pinion 92 meshing with a spur gear 93 keyed to a horizontal shaft 94 herein arranged in axial alignment with the shaft 88. Keyed to the shafts 88 and 94 are fast and slow speed worms 95 and 96 respectively which mesh respectively with the worm wheels 24 and 44 described above. The connections between the worm wheels 24 and 44 and the haulage drum are identical to those described above. It will thus be seen that the worm wheel 24 may be driven at a high speed through the gear train 14, 85, 86, 87, shaft 88 and worm 95, while the slow speed worm wheel 44 may be driven through the gear train 14, 85, 86, 87, 89, 90, 92 and 93. As the operation of this form of the mechanism is the same as that in the form described above, further description of the same is thought unnecessary.

As the mode of use of a longwall coal mining machine of the type disclosed herein is well understood to those skilled in the art, and as the operation of the improved plural speed transmission mechanism for driving the haulage drum at relatively high and low speeds has been clearly described above, a detail description of the mode of operation of the machine is considered unnecessary.

As a result of this invention, it will be noted that an improved mining machine feeding mechanism is provided which is of an extremely rugged and compact character especially adapted to use in coal mining machines of the longwall type wherein the spacial dimensions are restricted to a minimum. It will further be noted that by arranging the fast and slow speed worm gear trains in the manner disclosed and driving the feed drum by separate pinions engaging the drum driving gear and driving the worm gearing through the connections described, it has been found possible to materially reduce the number of moving parts while still retaining an improved plural speed drive and control. The various uses of the machine and various other advantages derived from this invention will be clearly apparent to those skilled in the art.

While I have in this application specifically described one form and a modification which the invention may assume in practice, it will be understood that this form and a modification are shown for purposes of illustration and that the invention may be further modified and embodied in various other forms without departing from its spirit or the scope of the appended claims.

What I claim as new and desire to secure by Letters Patent is:

1. In a mining machine, the combination with a feed operating member adapted to cooperate directly with flexible feeding means, of motor operated driving means for said feed operating member including a fast speed gear train and a slow speed gear train, each including a drive gear rotating about an axis lying in the longitudinal vertical center of the machine and both drive gears meshing with a gear common to both and rotatable with the feed operating member.

2. In a mining machine, the combination with a feed operating member adapted to cooperate directly with flexible feeding means, of motor operated driving means for said feed operating member including fast speed transmission means and slow speed transmission means, each transmission means including a drive shaft and a driven shaft, mechanism for rotating either drive shaft independently of the other, and mechanism individual to each transmission means for posi-

tively locking the shafts thereof together or to permit free relative rotation therebetween.

3. In a mining machine, the combination with a feed operating member adapted to cooperate directly with flexible feeding means, of motor operated driving means for said member including a fast speed transmission means and a slow speed transmission means, each of said transmission means including, and having individual thereto, a releasable positive interlocking mechanism and an operator controlled controlling clutch.

4. In a mining machine, the combination with a feed operating member adapted to cooperate directly with flexible feeding means, of motor operated driving means for said member including a fast speed transmission means and a slow speed transmission means, each of said transmission means including, and having individual thereto, an operator controlled positive interlocking mechanism and an operator controlled controlling clutch.

5. In a mining machine, the combination with a feed operating member adapted to cooperate directly with flexible feeding means, of motor operated driving means for said member including a fast speed transmission means and a slow speed transmission means, each of said transmission means including, and having individual thereto, a shaft, a friction clutch for connecting said shaft to its drive, a driven shaft, and an operator controlled connecting device for locking said shafts together or for permitting free relative rotation therebetween.

35 6. In a mining machine, the combination with a feed operating member disposed on a vertical axis and adapted to cooperate directly with flexible feeding means, of motor operated driving means for said member including a fast speed transmission means and a slow speed transmission means, each of said transmission means including a driving element, a driven shaft, clutch means for connecting said shaft to said driving element and a gear fixed to said shaft, and said feed operating member having a gear rotatable therewith and with which the gears of said transmission means mesh.

50 7. In a mining machine, the combination with a feed operating member adapted to cooperate directly with flexible feeding means, of motor operated driving means for said member including a fast speed gear train and a slow speed gear train, each of said gear trains including intermeshing worm gearing, and the worm wheels of said gearing rotating about parallel axes lying in the longitudinal vertical center of the machine.

60 8. In a mining machine, the combination with a feed operating member disposed on a vertical axis and adapted to cooperate directly with flexible feeding means, of motor operated driving means for said member including a fast speed gear train and a slow speed gear train, each of said gear trains including intermeshing worm gearing, and the worm wheels of said gearing rotating about parallel vertical axes.

70 9. In a mining machine, the combination with a feed operating member adapted to cooperate directly with flexible feeding means, of motor operated driving means for said member including a fast speed gear train and a slow speed gear train, each of said gear trains including intermeshing worm gearing, and the worms of said gearings rotating on aligned axes and the worm wheels rotating about parallel axes and lying in

the central longitudinal vertical plane of the machine.

10. In a mining machine, the combination with a feed operating member adapted to cooperate directly with flexible feeding means, of motor operated driving means for said member for driving the latter in a direction to draw in said flexible feeding means including relatively rotatable shafts arranged in axial alignment, fast and slow speed gears driven by said shafts respectively, gears meshing with said gears, and a gear rotatable with said feed operating member and driven by said last mentioned gears selectively.

11. In a mining machine, the combination with a feed operating member adapted to cooperate directly with flexible feeding means, of motor operated drive means for said member including a fast speed transmission mechanism and a slow speed transmission mechanism, said transmission mechanisms including coaxial worms and worm wheels meshing with said worms respectively and rotating on axes parallel with the axis of said feed operating member.

12. In a mining machine, the combination with a feed operating member adapted to cooperate directly with flexible feeding means, of motor operated drive means for said member including a fast speed transmission mechanism and a slow speed transmission mechanism, said transmission mechanisms including coaxial worms and worm wheels meshing with said worms respectively and rotatable about parallel axes parallel with the axis of said feed operating member.

13. In a mining machine, the combination with a feed operating member adapted to cooperate directly with flexible feeding means, of motor operated drive means for said member including a fast speed transmission mechanism and a slow speed transmission mechanism, said transmission mechanisms including coaxial worms and worm wheels meshing with said worms respectively and rotatable about parallel vertical axes parallel with the axis of said feed operating member.

14. In a mining machine, the combination with a feed operating member adapted to cooperate directly with flexible feeding means, of motor operated drive means for said member including a fast speed transmission mechanism and a slow speed transmission mechanism, said transmission mechanisms including coaxial worms and worm wheels meshing with said worms respectively and rotatable about parallel vertical axes lying in the central longitudinal vertical plane of the machine.

15. In a mining machine feeding mechanism, a feed drum disposed on a vertical axis, an internal gear fixed to said drum, gears meshing with said internal gear, a fast speed driving mechanism for one of said latter gears, and a slow speed driving mechanism for said other latter gear.

16. In a mining machine feeding mechanism, a feed drum, and plural speed driving means for said drum including a fast speed gear train and a slow speed gear train, said fast speed gear train including a worm and a worm wheel driven thereby, and said slow speed gear train including a worm wheel also meshing with said worm.

17. In a mining machine feeding mechanism, a feed drum, and plural speed driving means for said drum including a fast speed gear train

- and a slow speed gear train, said fast speed gear train including a worm and a worm wheel driven thereby and said slow speed gear train including a worm wheel meshing with said worm and rotating about an axis parallel to the axis of said first mentioned worm wheel. 80
18. In a mining machine feeding mechanism including a feed drum and plural speed driving means for said drum including coaxial worms, worm wheels meshing with said worms respectively and each operatively connectible to drive said drum and driving connections between one of said worms and said other worm including an element meshing with one of said worms. 85
19. In a mining machine feeding mechanism including a feed drum and plural speed driving means for said drum including coaxial worms, worm wheels meshing with said worms respectively and each operatively connectible to drive said drum, and driving connections between one of said worms and said other worm including a worm wheel meshing with the worm of the fast speed gearing. 90
20. In a mining machine feeding mechanism including a feed drum and plural speed driving means for said drum including coaxial worms, worm wheels meshing with said worms respectively and each operatively connectible to drive said drum, and driving connections between one of said worms and said other worm including a worm wheel meshing with the worm of the fast speed gearing, and a worm rotating about an axis parallel to said last mentioned worm wheel and a worm wheel meshing with said last mentioned worm. 95
21. In a mining machine feeding mechanism including a feed drum and plural speed driving means for said drum including coaxial worms, worm wheels meshing with said worms respectively and each operatively connectible to drive said drum, and driving connections between one of said worms and said other worm including a worm wheel meshing with the worm of the fast speed gearing, and a worm rotating about an axis parallel to said last mentioned worm wheel and a worm wheel meshing with said last mentioned worm and rotating on an axis coaxial with and driving the worm of said slow speed gear train. 100
22. In a mining machine, the combination with a feed operating member adapted to cooperate directly with flexible feeding means, of motor operated driving means for said feed operating member including a fast speed transmission mechanism and a slow speed transmission mechanism, said transmission mechanisms including coaxial worms relatively rotatable at different speeds, and worm wheels meshing with said worms respectively and selectively operatively connectible to said feed operating member. 105
23. In a mining machine, the combination with a feed operating member adapted to cooperate directly with flexible feeding means, of motor operated driving means for said feed operating member including a fast speed transmission mechanism and a slow speed transmission mechanism, said transmission mechanisms including coaxial worms relatively rotatable at different speeds, and worm wheels meshing with said worms respectively and rotatable about parallel axes, said worm wheels being operatively connectible to said feed operating member. 110
24. In a mining machine, the combination with a feed operating member adapted to cooperate directly with flexible feeding means, of motor operated driving means for said feed operating member including a fast speed transmission mechanism and a slow speed transmission mechanism, said transmission mechanisms including coaxial worms relatively rotatable at different speeds, and worm wheels meshing with said worms respectively and rotatable about parallel axes, said worm wheels being selectively operatively connectible to said feed operating member. 115
25. In a mining machine, the combination with a feed operating member adapted to cooperate directly with flexible feeding means, of motor operated driving means for said member including a fast speed transmission mechanism and a slow speed transmission mechanism, said transmission mechanisms including coaxial worms, one worm being driven by the other through reduction gearing, and worm wheels meshing with said worms respectively and selectively operatively connectible to said feed operating member. 120
26. In a mining machine, the combination with a feed operating member adapted to cooperate directly with flexible feeding means, of motor operated driving means for said member including a fast speed transmission mechanism and a slow speed transmission mechanism, said transmission mechanisms including coaxial worms, one worm being driven by the other through reduction gearing, and worm wheels meshing with said worms respectively and rotatable about parallel axes, said worm wheels being operatively connectible to said feed operating member. 125
27. In a mining machine, the combination with a feed operating member adapted to cooperate directly with flexible feeding means, of motor operated driving means for said member including a fast speed transmission mechanism and a slow speed transmission mechanism, said transmission mechanisms including coaxial worms, one worm being driven by the other through reduction gearing, and worm wheels meshing with said worms respectively and rotatable about parallel vertical axes, said worm wheels being operatively connectible to said feed operating member. 130
28. In a mining machine, the combination with a feed operating member adapted to cooperate directly with flexible feeding means, of motor operated driving means for said feed operating member including fast and slow speed gear trains including a worm, a worm wheel driven thereby, a worm driven by said worm wheel, a worm wheel driven by said last mentioned worm, a worm driven by said last mentioned worm wheel and arranged coaxially with said first mentioned worm, and worm wheels meshing respectively with said first mentioned worm and said last mentioned worm and selectively operable as feed operating member driving elements. 135
29. In a mining machine, the combination with a feed operating member adapted to cooperate directly with flexible feeding means, of motor operated driving means for said feed operating member including fast and slow speed gear trains including a worm, a worm wheel driven thereby, a worm driven by said worm wheel, a worm wheel driven by said last mentioned worm, a worm driven by said last mentioned worm wheel and arranged coaxially with said first mentioned worm, and worm wheels 140
- 75 30. In a mining machine, the combination with a feed operating member adapted to cooperate directly with flexible feeding means, of motor operated driving means for said feed operating member including fast and slow speed gear trains including a worm, a worm wheel driven thereby, a worm driven by said worm wheel, a worm wheel driven by said last mentioned worm, a worm driven by said last mentioned worm wheel and arranged coaxially with said first mentioned worm, and worm wheels 145
- 75 31. In a mining machine, the combination with a feed operating member adapted to cooperate directly with flexible feeding means, of motor operated driving means for said feed operating member including fast and slow speed gear trains including a worm, a worm wheel driven thereby, a worm driven by said worm wheel, a worm wheel driven by said last mentioned worm, a worm driven by said last mentioned worm wheel and arranged coaxially with said first mentioned worm, and worm wheels 150

meshing respectively with said first mentioned worm and said last mentioned worm, a gear fixed to said feed operating member, and gears driven by said last mentioned worm wheels respectively and meshing with said gear.

30. In a mining machine, the combination with a feed operating member adapted to cooperate directly with flexible feeding means, of motor operated driving means for said feed operating member including fast and slow speed gear trains, each gear train including, and having individual thereto, a driving element, coaxial relatively rotatable shafts, a clutch for connecting said driving element to one of said

10 shafts, and a clutch device for connecting said other shaft to said drive shaft for rotation therewith, and connections between said other shaft and said feed operating member.

31. In a mining machine, the combination with a feed operating member adapted to cooperate directly with flexible feeding means, of motor operated driving means for said feed operating member including fast and slow speed gear trains including coaxial relatively rotatable 20 gears, gears driven by said coaxial gears respectively, gears driven by said second mentioned gears respectively, and a gear fixed to said feed operating member and meshing with said last mentioned gears respectively.

30 32. In a mining machine, the combination with a feed operating member disposed on an axis lying in a vertical plane extending longitudinally of the machine and adapted to cooperate directly with flexible feeding means, of motor operated driving means for said feed operating member including a fast speed gear train, a slow speed gear train driven from a gear element of said fast speed gear train, said gear trains each having a terminal gear individual thereto, said terminal gears of the two trains being relatively rotatable; and driving connections between said terminal gears respectively and said feed operating member.

45 33. In a mining machine, the combination with a feed operating member disposed on an axis lying in a vertical plane extending longitudinally of the machine and adapted to cooperate directly with flexible feeding means, of motor operated driving means for said feed operating member including a fast speed gear train, a slow speed gear train driven from an element of said fast speed gear train, said gear trains including relatively rotatable gears, one in each train, and driving connections between said gears respectively and said feed operating member including a gear fixed to said feed operating member and with which both of said gears mesh.

60 34. In a mining machine, the combination with a feed operating member rotatable about a vertical axis and adapted to cooperate directly with flexible feeding means, and motor operated driving means for said feed operating member including shafts parallel with the axis of said feed operating member, a gear fixed to said feed operating member, gears driven by said shafts respectively and meshing with said gear, a fast speed gear train for one shaft and a slow speed gear train for the other shaft.

70 35. In a mining machine, the combination with a feed operating member rotatable about a vertical axis and adapted to cooperate directly with flexible feeding means, and motor operated driving means for said feed operating member

including shafts parallel with the axis of said feed operating member, a gear fixed to said feed operating member, gears driven by said shafts respectively and meshing with said gear, a fast speed gear train for one shaft and a slow speed gear train for the other shaft, and clutch devices for respectively connecting said shafts in driving relation with their respective gear trains.

80 36. In a mining machine, the combination with a feed operating member adapted to cooperate directly with flexible feeding means, of motor operated driving means for said feed operating member including shafts rotatable about parallel axes, driving elements coaxial with said shafts respectively, friction clutches for connecting said driving element to their respective shafts, driven elements coaxial with said shafts respectively, and clutch devices for connecting said shafts to their respective driven elements for rotation together and releasable at will to permit relative rotation therebetween, and driving connections between each of said driven elements and said feed operating member.

90 37. In a mining machine, the combination with a feed operating member adapted to cooperate directly with flexible feeding means, of motor operated driving means for said feed operating member including a fast speed transmission mechanism and a slow speed transmission mechanism, said transmission mechanisms including worms relatively rotatable at different speeds, and worm wheels rotatable about parallel vertical axes and meshing with said worms respectively, said worm wheels operatively connectible separately in driving relation with said feed operating member.

100 38. In a mining machine, the combination with a feed operating member adapted to cooperate directly with flexible feeding means, of motor operated driving means for said feed operating member including a fast speed transmission mechanism and a slow speed transmission mechanism, said transmission mechanism including worms disposed on horizontal axes and relatively rotatable at different speeds, and worm wheels rotatable about parallel vertical axes and meshing with said worms respectively, said worm wheels operatively connectible separately in driving relation with said feed operating member.

110 39. In a mining machine, the combination with a feed operating member adapted to cooperate directly with flexible feeding means, of motor operated driving means for said feed operating member including a fast speed transmission mechanism and a slow speed transmission mechanism, said transmission mechanisms including worms disposed on horizontal axes extending longitudinally of the machine and relatively rotatable at different speeds, and worm wheels rotatable about parallel vertical axes and meshing with said worms respectively, said worm wheels operatively connectible separately in driving relation with said feed operating member.

120 40. In a mining machine, the combination with a feed operating member adapted to cooperate directly with flexible feeding means, of motor operated driving means for said member including a fast speed transmission mechanism and a slow speed transmission mechanism, said transmission mechanisms including relatively rotatable worms, one worm driven by

- the other through reduction gearing an element of which meshes with the latter worm, and worm wheels meshing with said worms respectively and operatively connectible separately in driving relation with said feed operating member. 5
41. In a mining machine, the combination with a feed operating member adapted to cooperate directly with flexible feeding means, of motor operated driving means for said member including a fast speed transmission mechanism and a slow speed transmission mechanism, said transmission mechanisms including relatively rotatable worms disposed on horizontal axes, one worm driven by the other through reduction gearing an element of which meshes with the latter worm, and worm wheels meshing with said worms respectively and operatively connectible separately in driving relation with said feed operating member. 10
42. In a mining machine, the combination with a feed operating member adapted to cooperate directly with flexible feeding means, of motor operated driving means for said member including a fast speed transmission mechanism and a slow speed transmission mechanism, said transmission mechanisms including relatively rotatable worms rotatable on horizontal axes extending longitudinally of the machine, one worm driven by the other through reduction gearing an element of which meshes with the latter worm, and worm wheels meshing with said worms respectively and operatively connectible separately in driving relation with said feed operating member. 15
43. In a mining machine, the combination with a feed operating member adapted to cooperate directly with flexible feeding means, of motor operated driving means for said feed operating member including fast and slow speed gear trains including a gear, a gear meshing therewith and driven thereby, a gear driven by said second mentioned gear, a gear driven by said third mentioned gear, a gear driven by said fourth mentioned gear and arranged coaxially with and rotatable relative to said first mentioned gear, and gears meshing respectively with said first mentioned gear and said fifth mentioned gear and each connectible separately from the other to drive said feed operating member. 20
44. In a mining machine, the combination with a feed operating member adapted to cooperate directly with flexible feeding means, of motor operated driving means for said feed operating member including fast and slow speed gear trains including a gear, a gear meshing therewith and driven thereby, a gear driven by said second mentioned gear, a gear driven by said third mentioned gear, a gear driven by said fourth mentioned gear and arranged coaxially with and rotatable relative to said first mentioned gear, gears meshing respectively with said first mentioned gear and said fifth mentioned gear, a gear fixed to said feed operating member, and gears driven by said sixth and seventh mentioned gears respectively and both meshing with said last mentioned gear. 25
45. In a mining machine, the combination with a feed operating member adapted to cooperate directly with flexible feeding means, of motor operated driving means for said member including a fast speed gear train and a slow speed gear train, each of said gear trains includ- 30
- ing intermeshing gearing, the terminal gear of one gearing rotating about an axis parallel with that of the terminal gear of the other gearing and the axes of said terminal gears lying in the longitudinal vertical center of the machine. 35
46. In a mining machine, the combination with a feed operating member adapted to cooperate directly with flexible feeding means, and motor operated driving means for said feed operating member including a fast speed gear train and a slow speed gear train, each gear train including, and having individual thereto, a drive shaft disposed on a vertical axis, a coaxial relatively rotatable driven shaft, operative driving connections between said driven shaft and said feed operating member, a driving gear coaxial with said drive shaft, a clutch for connecting said drive shaft in driving relation with said driving gear, and an interlocking clutch mechanism for connecting said shafts directly together. 40
47. In a mining machine, the combination with a feed operating member adapted to cooperate directly with flexible feeding means, and motor operated driving means for said feed operating member including a fast speed gear train and a slow speed gear train, each gear train including, and having individual thereto, a drive shaft disposed on a vertical axis, a coaxial relatively rotatable driven shaft, operative driving connections between said driven shaft and said feed operating member, a driving gear coaxial with said drive shaft, a clutch for connecting said drive shaft in driving relation with said driving gear, an interlocking clutch mechanism for connecting said shafts directly together, and mechanism for controlling said clutch mechanisms operative always to connect said shafts directly together prior to the connection of said drive shaft with said driving gear. 45
48. In a mining machine, the combination with a feed operating member adapted to cooperate directly with flexible feeding means, of motor operated driving means for said feed operating member including a fast speed driving mechanism and a slow speed driving mechanism, each driving mechanism including a drive gear, a drive shaft coaxial therewith, a clutch for connecting said drive shaft in driving relation with said drive gear, a driven shaft coaxial with and rotatable relative to said drive shaft and interlocking clutch mechanism for connecting said shafts directly together, a gear driven by each driven shaft, and a gear fixed to said feed operating member and with which said last mentioned gears mesh. 50
49. In a mining machine, the combination with a feed operating member adapted to cooperate directly with flexible feeding means, of motor operated driving means for said feed operating member including a fast speed transmission mechanism and a slow speed transmission mechanism, each transmission mechanism including a shaft and said shafts being arranged on aligned axes, reduction gearing connecting one shaft in driving relation with the other shaft, worms driven by said shafts respectively, and worm wheels meshing with said worms respectively and operatively connectible separately in driving relation with said feed operating member. 55
